UNITED STATES PATENT OFFICE

ANTHONY C. McGINTY, OF LOS ANGELES, CALIFORNIA

ROTARY MOTOR

Application filed February 13, 1929. Serial No. 339,613.

This invention relates to rotary motors, and more especially to that class of rotary motors operating upon the turbine principle.

An object of the invention is the provision of a novel design of turbine, in which the housing and the rotor vanes are elongated, with the result that a greater area of vane may be exposed to the jets. This construction results in the development of a given amount of power by means of a turbine occupying a smaller space than one constructed according to conventional design.

A further object is the provision of a turbine of the general class described, which is composed of a very few parts, and which is of exceptionally simple design, with the result that a turbine embodying the principles of my invention, may be constructed at a relatively low cost, and still will operate with a high degree of efficiency.

A further object is the provision of a novel method of journalling the rotor shaft and of supplying the journals of the shaft with lubricant.

A still further object is the provision of a turbine of the general character described, in which the vanes are fluted on their trailing sides, the flutings extending in parallelism with the rotor shaft, the purpose being to add to the efficiency of the device by minimizing the "slippage" of the motive fluid in respect to the vanes.

A still further object is the provision of a turbine having an elongated tubular housing and a rotor shaft journaled co-axially thereof, and rotor vanes constructed in units of such a nature that additional units of vanes may be mounted on the shaft within the housing, and additional nozzles provided if it be desired to develop a greater amount of power with a given size of housing.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a top plan view of a turbine embodying the principles of my invention.

Fig. 2 is a side elevation taken in the direction of the arrow 2 of Fig. 1, and a portion of the housing being broken away to better disclose the nature of the invention.

Fig. 3 is a vertical, longitudinal sectional view taken upon the line 3—3 of Fig. 1, with the direction of view as indicated.

Fig. 4 is an end elevation taken in the direction of the arrow 4 of Fig. 3.

Fig. 5 is a vertical, transverse sectional view taken upon the line 5—5 of Fig. 3, with the direction of view as indicated.

Fig. 6 is a vertical, transverse sectional view taken upon the line 6—6 of Fig. 3, with the direction of view as indicated.

Fig. 7 is an end elevation taken in the direction of the arrow 7 of Fig. 3.

Specifically describing the preferred embodiment of the invention, the turbine comprises an elongated tubular housing indicated in its entirety at 11. Base flanges 12 rigid with the housing 11, provide a convenient means of support. As clearly shown upon Fig. 3, the housing 11 may conveniently be constructed of a length of tubing 13, cut to desired length.

The forward and after ends of the housing 11 are closed by heads 16 and 17 respectively, which are preferably tightly fitted into their associated ends of the tube 13, and each of which is provided with a flange 18 extending therefrom, adapted to engage the associated end of the housing and limit the distance that the head may be pressed into the housing. Any convenient means may be employed for rigidly securing the heads in position, such as screws 19 extending through the tube 13 into the associated head 16 or 17.

A partition 21 is also provided within the housing, this partition being fitted within the bore thereof and disposed between the heads 16 and 17, preferably closer to the forward head 16 than to the after head 17. A rotor shaft 22 is journaled within, and extends through the after head 17 and the partition 21. This shaft is disposed co-axially within the housing 11, and carries a rotor

unit 23 which comprises a plurality of radially extending vanes 24. Each of these vanes is extended in a direction parallel to the shaft 22, so that it is of greater width than length, the purpose being to permit the employment of at least two nozzles 26 disposed in a line parallel to the axis of the housing, to direct their jets simultaneously against the same vanes. Each of the vanes is provided with 10 preferably a pair of flutings 27, on its trailing side, and the extreme outer edge 28 of each vane, is deflected toward the trailing side of that vane, so that when fluid is directed against the trailing side by the nozzles 26, the amount of slippage of that fluid in respect 15 to the vane, will be reduced to a minimum, tending to produce a maximum torque upon the shaft 22, for a given volume and velocity of motive fluid.

20 All of the vanes 24 of the unit 23, are mounted in a unitary construction, being confined between discs 29 and 30. The unit is adapted to be rigidly attached to the shaft 22 in any convenient manner, such as by 25 soldering or brazing. The after disc 30 is provided with a plurality of apertures 31, one of these apertures 31 being disposed between each of the vanes 24, to permit the escape of motive fluid from the unit 23, after 30 having been directed against vanes 24.

Observation of Fig. 3, will disclose that the housing 13 is considerably longer than the unit 23. The purpose of this construction is to permit the employment of a plurality of the units 23, in the event that it is 35 desired to develop a greater amount of power with a motor of given size. It is to be understood that if additional units 23 are employed, additional nozzles 26 are also to be 40 provided.

Each of the nozzles 26 is in communication with a supply conduit 32 which may be connected to any suitable source of fluid under pressure. Furthermore, each of the 45 nozzles extends through the housing, with the axis of that nozzle disposed in angularity with a radius of the housing drawn from the point of entry of the nozzle into the housing, so that the jet from the nozzle will impinge 50 against the trailing side of the vanes 24, as the rotor unit 23 turns therewith.

The after head 17 is provided with an 55 elongated journal 36 through which a portion 37 of the shaft 22 of reduced diameter, extends. Races 38 and 39, rigid with the shaft 22 on opposite sides of the journal 36, confine ball bearings 41 and 42 between themselves and races 43 and 44 respectively, rigid with the head 17. Consequently, the 60 balls 41 and 42, co-acting with their associated races, serve as thrust bearings, preventing longitudinal displacement of the shaft 22 within the housing 11.

Any suitable means may be employed for 65 utilizing the power developed by the turbine,

as for example, a propeller 46 secured to the shaft 22, beyond the after head 17.

The partition 21 is also provided with an elongated journal 51, through which the forward end of the shaft 22 extends. An oil 70 passage 52 disposed axially within the shaft 22, extends from the forward end of the shaft through that portion thereof which is received within the journal 51. Oil ducts 53 lead from the passage 52 to the exterior of 75 the shaft within the journal 51. The forward head 16 is provided with a projection 56 on its inner face, which is pointed as at 80 57, so that the smaller end thereof may extend into the end of the oil passage 52. An oil passage 58 through the head 16 and projection 56, is thus brought into communication with the oil passage 32, so that lubricant, which may be supplied from any convenient 85 source such as an oil cup 59, may be fit into the oil passage 52 and thence through the ducts 53 to the journal 51. It is readily apparent that the forward head 16 may be removed, even during operation of the motor, to permit access to the partition 21 and that 90 end of the shaft 52, journalled therein, the partition 21 being fitted so tightly within the housing 11, that the motive fluid can not escape therewith into the chamber 61 between the partition 21 and forward head 16. Escape 95 of spent motive fluid from the housing 11, is provided for by means of an exhaust port 62 preferably adjacent that end of the housing 11 remote from the unit 23.

It is to be understood that the details of 100 the invention as herein disclosed, are subject to alteration within the spirit or scope of the appended claims.

I claim:

1. In a rotary motor, a housing comprising 105 an elongated tube, an after head and a forward head closing the associated ends of the tube, and a partition disposed within the tube between said heads and establishing a substantially fluid-tight seal between those portions of the tube on each side thereof, a rotor shaft disposed axially of said housing and journalled within and extending through said after head and said partition, a plurality of radiating vanes rigid with said shaft between 110 said partition and said after head, a nozzle adapted to direct its jet against the trailing sides of the vanes, and means for supplying fluid under pressure to said nozzle.

2. In a rotary motor, a housing comprising 115 an elongated tube, an after head and a forward head closing the associated ends of the tube, and a partition disposed within the tube between said heads and establishing a substantially fluid-tight seal between those portions of the tube on each side thereof, a rotor shaft disposed axially of said housing and journalled within and extending through 120 said after head and said partition, a plurality of radiating vanes rigid with said shaft 125 130

between said partition and said after head, a nozzle adapted to direct its jet against the trailing sides of the vanes, and means for supplying fluid under pressure to said nozzle, said forward head being removable to permit access to said partition and that end of the shaft journaled therein.

3. A rotary motor comprising a housing, a rotor shaft journaled therein, a rotor unit comprising a plurality of radiating vanes and securable to said shaft, said housing being elongated in a direction parallel to said shaft to a length at least twice that of said rotor unit whereby a plurality of such units may be mounted upon the shaft, and means for directing fluid against the vanes of the unit proximal to one end of the housing, the other units being adapted to receive fluid therefrom when mounted upon said shaft.

20 In testimony whereof I have signed my name to this specification.

A. C. McGINTY.
